(57) **CLAIM**

The ornamental design for a guitar pickup, as shown and described.

DESCRIPTION

FIG. 1 is a perspective view of my new design;

FIG. 2 is a front view thereof;

FIG. 3 is a rear view thereof;

FIG. 4 is a bottom view thereof;

FIG. 5 is a top view thereof;

FIG. 6 is a left-side view thereof; and,

FIG. 7. is a right-side end view thereof.

The broken lines represent the portions of the guitar pickup that form no part of the claimed design.
